(57) **CLAIM**

The ornamental design for “waterproof LED lamp tube,” as shown and described.

DESCRIPTION

FIG. 1 is a perspective view of “waterproof LED lamp tube” showing my new design thereof, with the center portion broken away to indicate indeterminate length;
FIG. 2 shows a right side view thereof;
FIG. 3 is a top view thereof;
FIG. 4 is a front side elevation view thereof;
FIG. 5 is a bottom plan view thereof;
FIG. 6 is a left side elevation view thereof; and
FIG. 7 is a rear perspective view; and
FIG. 8 is another perspective view thereof.
